UNITED STATES PATENT OFFICE.

ROBERT J. WATERWORTH, OF SIDNEY, OHIO, ASSIGNOR OF ONE-HALF TO L. M. STUDEVANT, OF SIDNEY, OHIO.

ROTARY FEEDER.

Application filed October 5, 1926. Serial No. 132,735.

My invention relates to feeder heads. It is the object of my invention to provide a feeder head adaptable for use in connection with a machine such as shown in my pending application, Serial No. 60,327.

The specific object of the present invention is to provide a feeder head which will operate twice as rapidly with a given circumference of head and in particular which will lift the forward edge of each sheet away from the other sheets on which it is stacked, positively breaking that edge away from the remaining sheets.

Referring to the drawings:

Fig. 1 is a side elevation of my feeder head as mounted upon a feeding machine;

Fig. 2 is a side elevation of the feeder head in detail with its supporting shaft in section and with a portion of its structure broken away showing in section its mechanism for picking up the topmost sheet;

Fig. 3 is a bottom plan view of the periphery of the feeder showing the arrangement of the suction apertures adjacent the flattened portion of the feeder head;

Fig. 4 is a section of the line 4—4 of Fig. 1.

Fig. 5 is an elevation of the buckling mechanism partially broken away.

Fig. 6 is a section of the line 6—6 of Fig. 2.

Referring to the drawings in detail, 1 is a supporting frame on which is supported on the shaft 2 the swinging feeder head support 3, which has a yoke carrying the drive-shaft 4 which actuates the feeder head 5. Yoke 3 is referred to as a swinging yoke because it may be positioned as desired with respect to the sheets to be fed. The open end of a suction line 6 is held in position by the depending arm 7 of the swinging yoke 3 so that the open end of the suction line will be held opposite to the suction openings 8 and relief grooves 9, both of which are cut in the side wall of the feeder head 5. These holes 8 communicate with radially disposed passageways 10 which open on the periphery 11 of the feeder head. One of these passageways is provided with diagonally disposed communicating passageways 12, the outer ends of which communicate with a flattened portion 13 on the periphery of the feeder head, such flattened portion being provided with a shoulder 14 at one end thereof against

which the end of the topmost sheet 15 is adapted to engage.

When suction is applied through the passageways 12 the forward edge of the topmost sheet is bent upwardly at an angle to the remaining sheets and the sheet is thus positively broken away so that the air from the fluttering device designated 16 may pass between the bottom of the topmost sheet 15 and the remaining sheets, thus easily separating the sheets allowing the topmost sheet to be removed from the stack of sheets remaining and move to its final fed position. The fluttering head 16 may be fed from any suitable source of supply of air through the pipe 17.

When it is desired to relieve the suction the feeder head is so arranged that the suction pipe 6 will have its head over the relief grooves 9. This release of the suction on the passageways 10 releases the sheet which has been fed to its final position. By putting a number of such groups of passageways 10 around the periphery of the feeder head it is possible to multiply the number of sheets which can be fed by a given revolution of a head of a given diameter.

Mounted on the shaft 4 is a driving gear 18 which drives a gear 19 journalled in the yoke 3 on the stub shaft 20. This gear 19 carries with it a buckling disc 21 the inside face of which slidably engages the adjacent face of the feeder head 5. The buckling disc is provided with a side aperture 22 communicating with a passageway 23, which opens at 24 on the periphery of the shield 21 and is adapted to engage at a given interval with the topmost sheet to move it backwardly, contrary to the direction of its being fed in order to buckle the sheet to loosen it from the stack of sheets on which its rests. Suction is applied through the passageways 22 and 23 when 22 coincides with the transverse passageway 25 in the feeder 5. This passageway communicates with the horizontal passageway 28 in the suction head 6. It will be noted as the gearing is arranged the disc 21 will turn in the reverse direction to that of the feeder head 5 and will engage the topmost sheet and move it backwardly to buckle it to loosen it from the other sheets before the final feeding operation by the feeder head 5.

There will be passageways 27, 26 and 25

associated with each group of passageways 10.

It will be understood that I desire to comprehend within my invention such modifications as may be found desirable in order to adapt my invention to various conditions and use.

Having thus fully described my invention, what I claim as new and desire to secure by 10 Letters Patent is:

1. In a feeder, a rotary feeding head, a flattened portion on the periphery thereof said head having supplementary suction passageways communicating with said flattened portion, a main suction passageway communicating with the periphery of the feeder head, a suction means adapted to apply suction to said passageways whereby the leading edge of a sheet to be fed will 20 be drawn against the flattened portion of the feeder head and bent at an angle to the sheets upon which it rests.

2. In a feeder, a rotary feeder head a flattened portion on the periphery thereof, said head having suction passageways a portion of which communicate with the flattened portion of the periphery and a portion of which communicate with the rounded portion of the periphery, means to apply suction to such passageways, said feeder head having a suction groove on the side thereof adapted to release the suction of the suction means.

3. In a feeder, a rotary feeder head a flattened portion on the periphery thereof, said head having suction passageways a portion of which communicate with the flattened portion of the periphery and a portion of which communicate with the rounded portion of the periphery, means to apply suction to such passageways, said feeder head having a suction groove on the side thereof adapted to release the suction of the suction means, means to move a sheet to be fed in the reverse direction to that in which it is to be fed to buckle the sheet, said means having a suction passageway therethrough, and said feeder head having means to coincide therewith at a point adjacent the flattened portion of periphery on the feeder head to cause said buckling just prior to bending the sheet against the flattened portion of the periphery of the feeder head.

4. In combination in a feeder of a rotary feeder head having a flattened portion on the periphery and a plurality of suction apertures communicating with the periphery and the side of the feeder head, a portion of said passages communicating with the flattened portion of the periphery and a portion with the curved part of the periphery; suction means adapted to be intermittently connected to the apertures on the side of the feeder head, said feeder head having a suction relief groove on the side thereof, means

to flutter the sheets being fed by the feeder head.

5. In combination in a feeder of a rotary feeder head having a flattened portion on the periphery and a plurality of suction apertures communicating with the periphery and the side of the feeder head, a portion of said passages communicating with the flattened portion of the periphery and a portion with the curved part of the periphery; suction means adapted to be intermittently connected to the apertures on the side of the feeder head, said feeder head having a suction relief groove on the side thereof, means to flutter the sheets being fed by the feeder head, suction means moving in the reverse direction to the direction of rotation of said feeder head, a common power means for operating the feeder head and the reverse mechanism, said reverse mechanism having the same suction means as the feeder head, said feeder head having a passageway therethrough for communicating the suction from the suction means to the reverse means.

6. In a feeder, a disc having an aperture therethrough from side to side and a plurality of apertures on the side thereof communicating with the periphery of the disc, a portion of said apertures communicating with the rounded portion of the periphery and another portion communicating with the flattened portion of the periphery, the flattened portion of the periphery having a shoulder at one end and suction means adapted to slidably engage the side of said feeder head over said apertures, said feeder head having means to release said suction when the suction means has been displaced from the apertures on the side of the head.

7. In a feeder, a disc having an aperture therethrough from side to side and a plurality of apertures on the side thereof communicating with the periphery of the disc, a portion of said apertures communicating with the rounded portion of the periphery and another portion communicating with the flattened portion of the periphery, a flattened portion of the periphery having a shoulder, at one end and suction means adapted to slidably engage the side of said feeder head over said apertures, said feeder head having means to release said suction when the suction means has been displaced from the apertures on the side of the head, a buckling disc slidably engaging the side of the feeder head opposite to the suction means, said buckling disc having an aperture through the side to the periphery thereof, the side aperture being adapted to engage with the first-mentioned side aperture through the feeder head, and a common driving means for the feeder head and the reverse means whereby said feeder head and reverse means operate in opposite direction and are intermittently and successively oper-

ated with said suction means to buckle and inject a sheet.

8. A new article of manufacture for use as a feeder head, consisting of a disc having a periphery with flattened portions and shoulders adjacent said flattened portions and a plurality of suction passageways, a

portion of which connect with the flattened periphery and a portion with the rounded periphery of the feeder, all of said passageways communicating with apertures on the side of the feeder. ¹⁰

In testimony whereof, I affix my signature.
ROBERT J. WATERWORTH.
